UNITED STATES PATENT OFFICE.

FREDERICK ARIMOND, OF CENTRAL TANAMO, CUBA.

SAW.

Application filed November 18, 1925. Serial No. 69,859.

This invention relates to a saw device, the general object of the invention being to provide means whereby trees may be sawed down and logs and other timber sawed into lengths very easily and quickly, by an operator seated on a part of the supporting frame of the device, the operator rotating the saw blade by means of a foot pedal and moving the blade toward and away from the work piece by means of hand operated means.

Another object of the invention is to provide means whereby the blade can be held in either a horizontal or a vertical position.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawings wherein like characters denote like or corresponding parts throughout the several views, and in which:—

Figure 1 is an elevation of the device.

Figure 2 is a plan view.

Figure 3 is a vertical sectional view through the blade supporting and operating means.

Figure 4 is a section on line 4—4 of Figure 3.

In these views, 1 indicates a tripod-like frame, the legs of which are telescopic so that the frame can be adjusted on uneven ground to make the seat 2 at the converging portions of the legs level as well as the saw supporting means. The front leg of the frame is formed with a substantially rectangular shaped part 3 which forms a bearing for a crank shaft 4, pedals 5 being connected with the ends of the cranks. A large gear 6 is fastened to the shaft. These parts are so arranged that a person sitting on the seat 2 can place his feet on the pedal and thus rotate the crank shaft and the gear by a movement of his feet. An upright frame 7 is formed on the lower end of the front leg of the main frame, and this frame 7 is formed with a guideway 8 for a rod 9 and with a bearing 10 for a hollow shaft 11 which has a pinion 12 at its inner end engaging the gear 6. A shaft 13 is slidably mounted in the hollow shaft and is keyed thereto so that it must rotate with said hollow shaft 11. This shaft 13 has a beveled pinion 14 on

its outer end. The rod 9 has its outer end bent upwardly and formed with a yoke 9' through one prong of which the shaft 13 passes and through the other prong of which a spindle 15 passes, the spindle being held in this prong by the nuts and washers 16. This spindle extends horizontally from a vertically arranged hub 17 which has a socket therein which is arranged diametrically opposite the spindle and receives a projection 18, at the center of the pinion 14. The lower end of a saw shaft 19 is journaled in the hub and the upper end of this shaft is journaled in an arm 20 which is rotatably supported on the bearing 10 of shaft 11. The saw blade 22 is fastened to the shaft by means of the nut and washer 23 which presses the blade against a gear 24 on the shaft, said gear meshing with the gear 14.

From the foregoing, it will be seen that when the pedals are actuated, the movement of the crank shaft will be communicated to the saw shaft through the gears 6 and 12, shafts 11 and 13 and the gears 14 and 24.

When the saw is in a horizontal position, as shown in the drawings, the device can be used for sawing down trees, posts and the like, and when it is desired to saw up logs and the like, the nut 16 is loosened so that the hub 17 can be given a quarter turn to place the saw blade in a vertical position. Then the nut is tightened to hold the parts in this position. As will be seen, the arm 20 moves with the saw shaft, its inner part turning on part 10 of the frame 7.

The saw blade can also be moved toward and away from its work through means of the sliding bar 9 and the telescopic shafts 11 and 13. The parts are held in retracted position by the spring 25 on the rod 9 and a cable 26 which is fastened to the rear end of the rod 9 and passes over the guiding pulleys 27, is provided for moving the parts forwardly against the action of the spring when a handle 28 on the cable is pulled by the operator. This spring is a coiled spring arranged on the rod 25 and having one end bearing against a part of the frame 7 and its other end bearing against a collar or projection on the rear end of the rod 9 so that said spring normally holds the rod in its rearward position.

Suitable lubricant is supplied to the saw blade by means of the cup 29 and the tubes 30 containing wicks which contact with the saw teeth, and the various rotary members

are provided with ball bearings 31 for reducing friction to a minimum.

Thus I have provided an effective structure for operating a saw by the feet of the operator, the operator sitting down with his hands free to move the saw to and from its work. Of course, if desired, a motor may be attached to the crank shaft so that the saw will be power driven, and the parts may be so arranged that a number of men can sit on the frame and operate crank shafts for driving the saw, where one man would be unable to do the work by himself.

It will, of course, be understood that the saw can be held at any intermediate point between the vertical and horizontal, if desired.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:—

1. A saw device comprising a frame, a tubular shaft journaled in said frame, a second shaft slidably and non-rotatably mounted in the first shaft, a beveled gear on the outer end of the second shaft, a member slidably mounted in the frame and having a yoke-shaped part through one prong of which the second shaft passes, a hub having a part rotatably engaging a projecting part on the gear, a spindle on the hub passing through the other part of the yoke, means for rotatably connecting the spindle with said part of the yoke, a saw arbor rotatably mounted in the hub, a beveled gear carried thereby and meshing with the first gear, a saw carried by the arbor, means permitting the slideable member to be moved to cause its yoke part to move the saw outwardly against the work and means for rotating the tubular shaft.

2. A saw device comprising a frame, a tubular shaft journaled in said frame, a second shaft slidably and nonrotatably mounted in the first shaft, a beveled gear on the outer end of the second shaft, a member

slidably mounted in the frame and having a yoke-shaped part through one prong of which the second shaft passes, a hub having a part rotatably engaging a projecting part on the gear, a spindle on the hub passing through the other part of the yoke, means for rotatably connecting the spindle with said part of the yoke, a saw arbor rotatably mounted in the hub, a beveled gear carried thereby and meshing with the first gear, a saw carried by the arbor, means permitting the slideable member to be moved to cause its yoke part to move the saw outwardly against the work, means for rotating the tubular shaft and an L-shaped arm having a bearing at one end for engaging the part of the frame which forms a bearing for the tubular shaft and its other end forming a bearing for the saw arbor.

3. A saw device comprising a frame provided with legs, a front upright extension on the frame having a horizontal bearing at its upper end and a horizontal guideway below the bearing, a rod slidably mounted in the guideway and having its outer end bent at right angles and formed with a yoke, a spring on the rear part of the rod for holding the same in its rearward position with one prong of the yoke engaging the front end of the bearing, a tubular shaft rotatably mounted in the bearing, a solid shaft slidably and non-rotatably mounted in the tubular shaft, said solid shaft passing through the inner prong of the yoke, a gear on the outer end of said solid shaft, a hub rotatably mounted on a projection at the center of the gear, a spindle on the hub rotatably connected with the outer prong of the yoke, a saw arbor journaled in the hub, a saw carried thereby, a drive shaft mounted in the frame, gears connecting the same with the tubular shaft, a cable connected with the rear end of the slideable rod and passing over pulleys on the frame parts for projecting the rod when the cable is pulled upon, spring means for holding the rod in retracted position and a seat on the frame.

In testimony whereof I affix my signature.

FREDERICK ARIMOND.
